MACHINE FOR WASHING GLASSES AND
OTHER RECEPTACLESCresson J. de Forest, Bogota, N. J., assignor of
one-half to Edward L. Corbett, New York,
N. Y.

Application August 31, 1932. Serial No. 631,277

12 Claims. (Cl. 15—76)

My invention relates broadly to washing machines and more particularly to a machine for rapidly cleansing glasses and other containers.

One of the objects of my invention is to provide a washing machine for glasses and other receptacles in which a positive brushing action may be obtained against both the inside and outside of the glass or the receptacle.

Another object of my invention is to provide a machine for washing glasses and receptacles in which operation of the washing machine may be effected by downward pressure exerted on the operating brush of the washing machine as the glass or receptacle is inserted over the operating brush in the process of cleansing the article being subjected to the washing operation.

Still another object of my invention is to provide a simplified construction of washing machine for glasses or other receptacles in which a rotary driving mechanism is operated by the pressure of the glass or receptacle against the cleaning elements of the washing machine for positively cleansing both the inside and outside of the article being acted upon by the washing machine.

A further object of my invention is to provide an improved fountain brush mechanism for subjecting glasses and other receptacles to a rotary abrading action on both the inside and outside thereof, at the same time supplying cleansing fluid to the brush, the cleansing fluid being directed through ports in the driving mechanism so located as to avoid clogging of the ports from sediment resulting from cleaning of successive articles.

A still further object of my invention is to provide a construction of rotary brush mechanism for cleaning glasses and other receptacles in which the elements of the brush mechanism are readily renewable under conditions of extended wear of the brush elements.

Another object of my invention is to provide a construction of renewable roller bearing for the rotary drive mechanism of a fountain brush whereby friction is substantially reduced for eliminating wear upon the revolving parts even under conditions of extended use of the fountain brush.

Still another object of my invention is to provide an arrangement of spring mechanism which permits extensive vertical movement of a rotary brush carrier and continuously acts upon the rotatable carrier for normally projecting the brush above the surface of a fluid bath into which the brush is successively plunged as pres-

sure is applied thereto through a glass or other receptacle in the process of cleaning.

Other and further objects of my invention reside in the construction of a fountain brush adapted to be inexpensively manufactured on a quantity production basis according to the construction described in the following specification and referred to in the accompanying drawings, in which:

Figure 1 is a side elevation partially in section 65 of the washing machine showing a drinking glass in position thereon; Fig. 2 is a similar view partially in section showing the centrally disposed cleaning brush depressed to its extreme position so as to expose the inner and outer surfaces of 70 the drinking glass to a scrubbing action of the rotating brushes; Fig. 3 is a horizontal sectional view taken on line 3—3 of Fig. 1; Fig. 4 is a horizontal sectional view taken on line 4—4 of Fig. 1; Fig. 5 is a central vertical longitudinal 75 sectional view upon an enlarged scale taken substantially on line 5—5 of Fig. 1 and showing the drinking glass washer disposed within the sink filled partly with water; Fig. 6 is a view showing the various parts comprising the washer in side 80 elevation and in juxtaposition to each other; Fig. 7 is a horizontal sectional view through the brush taken on line 7—7 of Fig. 5; Fig. 8 is a horizontal sectional view taken on line 8—8 of Fig. 5; Fig. 9 is a horizontal sectional view taken 85 on line 9—9 of Fig. 5; and Fig. 10 is a horizontal sectional view taken on line 10—10 of Fig. 5.

Referring to the drawings in detail, reference character 1 designates a base support which rests upon the bottom of the pail, tub or sink, 90 designated generally at 2.

A suction cup 3 is provided for securely anchoring the base 1 in position. An upwardly extending tubular member 4 is carried by the base 1, which member is provided with a pair of annular 95 flanges 5 adjacent the top and bottom thereof. The upwardly extending tubular member 4 is provided with a spiral slot 6 therein, which slot serves as a guide for the roller 7 which is supported upon radially extending pin 8 which projects from the sleeve member 9. The sleeve member 9 has a diameter of such size that the sleeve member is adapted to slide telescopically with respect to the upwardly extending tubular member 4. In order to guide the sleeve 9 I provide a vertically disposed rod member 10 which is anchored to the base 1 in any suitable manner as represented at 11 and is provided with a head 12 which fits tightly within the sleeve and serves 100 as a piston or plunger to force water or other 105 110

cleaning fluid upwardly through the sleeve when the sleeve is pressed downwardly. The head 12 provides a limiting stop for the one end of the coil spring 14 which is disposed concentrically 5 within the sleeve 9. The upper end of the sleeve 9 is internally screw threaded as represented at 15 and receives a screw threaded member 16, which is provided with ports 17 therein so that cleaning fluid forced upwardly through the sleeve 10 by the head 12 may pass outwardly and onto the upper bristles of the rotatable brush 18. A stop 19 is secured to the screw threaded member and serves as an abutment against which the bottom 15 of the glass or receptacle seats when the glass or receptacle 20 is moved into position over the rotatable brush as shown more clearly in Figs. 1 and 2.

The rotatable brush 18 is constituted by a plurality of removable sections. Fig. 7 illustrates 20 more clearly the arrangement of the sections. Sleeve 9 carries radially disposed socket members 9a, 9b and 9c into which the strips 18a, 18b, and 18c carrying radially disposed bristles are slidable. The bristles making up the rotatable brush 18 are therefore readily renewable 25 by removing the carrier strips 18a, 18b and 18c from sockets 9a, 9b and 9c and inserting fresh strips carrying new bristles. The coil spring 14 heretofore described tends to normally project 30 the rotatable brush 18 in a position above the level of the fluid indicated at 21 in the fluid bath. However when a glass or other receptacle 20 is inserted over the rotatable brush 18 as indicated in Figs. 1 and 2 and pressure applied to the 35 glass or other receptacle by the hand of the operator as represented in Figs. 1 and 2, the rotatable brush is caused to move to a position below the surface of the fluid 21 while the rotatable brush 18 is positively driven. The positive 40 driving action is obtained as heretofore explained by roller 7 traveling downwardly along spiral groove 6. The abutment 19 against which the glass or other receptacle rests is freely revolvable 45 in the screw threaded member so that the glass or other receptacle 20 remains stationary as supported by the abutment 19 while brush 18 freely revolves interiorly of the glass or other receptacle. Tubular member 9 has an aperture 50 22 formed therein substantially above the roller bearing 8 through which the cleansing fluid is free to pass.

It will be observed that passage 22 is at all 55 times disposed at a level substantially above the bottom of the pail, tub or sink 2, even when the brush 18 has been depressed to its extreme lower position as illustrated in Fig. 2. By this arrangement sediment, dirt or other accumulation at the bottom of the pail, tub or sink does not stop the free flow of fluid through 60 sleeve 9 and out through apertures 17 in the screw threaded member 16. When sleeve 9 is depressed to the position illustrated in Fig. 2, coil spring 14 has potential energy stored therein tending to restore brush 18 to elevated position 65 immediately after pressure is removed therefrom. Brush 18 serves to clean the interior of the glass or other receptacle 20. In order to clean the exterior thereof I provide an external brush having horizontally extending inwardly directed 70 bristles represented at 23 disposed in a carrier 24 mounted in a retaining ring member 25. The retaining ring member 25 is connected at diametrically opposite positions thereof by means of strip members 26 extending from the ring member 25 to a sleeve 27. The sleeve 27 is

concentrically disposed over the upwardly extending tubular member 4 and confined in position with respect thereto at its lower portion on anti-friction rollers 28. The anti-friction rollers 28 are carried by ring member 29 which is secured by any suitable means such as screw members 29a to base 1. The lower edge of sleeve 27 rolls over the roller members 28. The sleeve 27 is driven over roller members 28 by the engagement of roller 7 with the spiral slot 30 in sleeve 27. The spiral slot 30 is angularly pitched in a direction opposite to the direction of the pitch of spiral slot 6 in the upwardly extending tubular member 4. The arrangement is such that downward movement of roller 7 operates to revolve brush 18 through the coaction of roller 7 with spiral slot 6 and simultaneously brush 23 is revolved in the same direction but at a different rate of speed through the coaction of roller 7 with spiral slot 30 in sleeve 27. The sleeve 27 is confined in position on upwardly extending tubular member 4 by radially extending pins 31. In order to permit discharge of the cleansing fluid from upwardly extending tubular member 4, a port 32 is provided adjacent 100 the base thereof as shown. It will be observed that the bristles of the brushes 23 and 18 overlap in a position above the fluid level 21 and as the glass or other receptacle is inserted over brush 18 and pressed downwardly, both the interior and exterior surfaces thereof are thoroughly cleaned including the lip contact portion of the glass or receptacle. This avoids the usual manner of cleaning which requires hand washing at the edge of the glass which is a 110 dangerous and time consuming operation.

The apparatus of my invention is therefore highly sanitary and is capable of use where glasses or other receptacles must be washed at relatively high speed. Fig. 3 indicates the manner in which 115 the brushes 23 and 18 are driven at different rates of speed for cleaning the exterior and interior surfaces simultaneously. The frame structure which supports the exterior parts 23 has the elements 26 thereof so shaped that only the thin edges of the strips 26 are presented to the cleansing fluid so that rotation of the exterior brush does not create excessive agitation or produce undesirable retarding action during the operation 120 of the brushes. It will be observed that the structure of the brush is such that replacement elements of selected dimensions may be inserted in the sockets which carry the brush elements. In this way the washer may be applied for the cleaning 125 of various sized containers or vessels.

I have found the apparatus of my invention highly practical in its construction and operation and while I have described my invention in certain preferred embodiments, I desire that it be understood that modifications may be made and that no 135 limitations upon my invention are intended other than are imposed by the scope of the appended claims.

What I claim as new and desire to secure by Letters Patent of the United States is as follows: 140

1. A washing machine for glasses and other receptacles comprising a vertically extending tubular support having a spiral slot disposed therein, a rotatable tubular carrier concentrically disposed within said tubular support, a roller member extending radially from said carrier and projecting through the spiral slot in said vertically extending tubular support, a brush carried by said tubular carrier, an independent rotatable sleeve concentrically disposed over said vertically extending 145 150

- tubular support and having a spiral slot therein engaging the roller member on said rotatable carrier, and a brush supported by said independent sleeve in cooperative relation to the brush carried by said tubular carrier for rotatably acting upon the interior and exterior surfaces of a glass or other receptacle inserted over said first mentioned brush and subjected to axial pressure for imparting simultaneous rotary motion to each of said brushes. 5
2. In a machine for washing glasses and other receptacles, a vertically disposed tubular support, a rotatable carrier concentrically disposed within said support and adapted to be slid vertically in the support and rotated relative to said support during sliding movement, a brush mounted on the upper end of said carrier and adapted to impart an abrading action to the interior surface of a glass or other receptacle inserted thereover, an external brush independent of the first brush and having a shank rotatable about said support and adapted to engage the exterior surface of the glass or other receptacle, and means operative by the application of pressure in an axial direction against said rotatable carrier for simultaneously imparting rotary movement to the external brush and internal brush at different speeds relative to each other and cleansing both sides of said glass or other receptacle. 10
3. In an apparatus of the class described, a cylindrical supporting member, a rotatable sleeve mounted interiorly of said cylindrical supporting member and slidably vertically therein, a rotatable sleeve mounted exteriorly of said cylindrical supporting member, a rotatable brush carried by each of said rotatable sleeves, and a pin carried by the inner sleeve and engaged in tracks formed spirally in the supporting member and outer sleeve for imparting rotation to the sleeves and brushes when the inner sleeve is slid vertically in the supporting member. 15
4. A washing machine for glasses comprising a support adapted to be submerged in a fluid bath and having a vertically disposed tubular standard, a rotatable brush having a tubular shank slidably received in said standard, a plunger extending vertically in the standard and slidably fitting in the lower end of said shank, a spring for normally elevating said brush above the surface of the fluid bath disposed within the shank and resting upon said plunger, and means for imparting rotary motion to the shank and brush when the brush and shank are moved downwardly by application of pressure to the shank by the insertion of a glass in an inverted position over the brush. 20
5. A washing machine for glasses comprising a support adapted to be submerged in a fluid bath and having a vertically disposed tubular standard, a rotatable brush having a tubular shank slidably received in said standard, a plunger extending vertically in the standard and slidably fitting in the lower end of said shank, a spring for normally elevating said brush above the surface of the fluid bath disposed within the shank and resting upon said plunger, and means for imparting rotary motion to the shank and brush when the shank and brush are moved downwardly by application of pressure to the shank by the insertion of a glass in an inverted position over the brush, the lower portion of the shank being formed with a fluid inlet in its side closed by walls of the standard when the shank is moved downwardly into the standard and the upper portion of the shank having outlets for discharging fluid upon the brush and glass as the plunger rises in the shank above the inlet during downward movement of the shank. 25
6. In a machine for washing glasses, a tubular standard adapted to be submerged in a fluid bath, a rotatable internal brush having a shank slidably and rotatably received in said standard, means for normally projecting said brush upwardly to an elevated position above the standard, an external brush having a tubular shank rotatably disposed about said standard, the shank of the internal brush having means cooperatively engaged with the standard and shank of the external brush to simultaneously impart rotation to the brushes when the internal brush is forced downwardly by application of pressure exerted when a glass is disposed in an inverted position about the internal brush and pressed downwardly. 30
7. In a machine for washing glasses, a tubular standard adapted to be submerged in a fluid bath, a rotatable internal brush having a shank slidably and rotatably received in said standard, means for normally projecting said brush upwardly to an elevated position above the standard, an external brush separate from the internal brush and rotatable about the internal brush and standard, and actuating means carried by the shank of the internal brush and cooperating with the standard and external brush to impart rotation to the brushes at different speeds relative to each other when the internal brush is forced downwardly by pressure applied to a glass disposed in an inverted position over the internal brush. 35
8. In a machine for washing glasses, a tubular standard adapted to be submerged in a fluid bath, a rotatable internal brush having a shank slidably and rotatably received in said standard, means for normally projecting said brush upwardly to an elevated position above the standard, an external brush separate from the internal brush and rotatable about the internal brush and standard, and actuating means cooperating with the standard for imparting rotation to the brushes at different speeds relative to each other when the internal brush and its shank are reciprocated in the standard. 40
9. In an apparatus of the class described, a vertically disposed tubular support, a rotatable carrier telescopically mounted within said support and slidably vertically therein, an independent rotatable carrier rotatably disposed about said support and held against vertical movement, independent cleaner members supported by said carriers for operating upon internal and external surfaces of a glass, and means operated by downward pressure applied to the first mentioned carrier for imparting rotary movement to the cleaner members of the carriers independent of each other and effecting a cleaning operation upon inner and outer surfaces of a glass as the first mentioned carrier moves vertically. 45
10. In an apparatus of the class described, a vertically disposed tubular supporting member, inner and outer rotatable carriers concentrically mounted one within and the other about said supporting member, the inner carrier being slidable axially through said supporting member and having means for simultaneously imparting rotation to both carriers when the inner carrier is moved vertically by pressure applied against its upper end, the outer carrier being held against vertical movement, and cleaner members carried by each of said carriers for effecting a cleaning 50

operation upon inner and outer surfaces of a glass disposed in an inverted position over the inner carrier.

11. In an apparatus of the class described, a cylindrical supporting member, a pair of tubular members concentrically positioned with respect to said cylindrical supporting member and rotatable relative thereto, one of said tubular members being disposed interiorly of said supporting member and shiftable axially with respect thereto, and the other tubular member fitting about the supporting member and held against axial shifting, a brush carried by the inner tubular member, an annular brush disposed in a substantially horizontal plane about the first brush, arms for supporting the annular brush extending downwardly therefrom and carried by the outer tubular member, said arms supporting the annular brush in position for coacting with the first mentioned brush and cleaning inner and outer surfaces of a glass disposed in an inverted position over the first brush with its walls extending between the brushes, and means cooperating with the supporting member and tubular members to rotate the brushes when the inner tubular member and its brush are reciprocated.

12. In an apparatus of the class described, a vertically disposed cylindrical support, a pair of rotatable sleeves concentrically mounted, one interiorly and the other exteriorly of said support, the interior sleeve being slideable vertically in said support, a passage for fluid extending through the interior sleeve and having an outlet at its upper end and an inlet adjacent its lower end and opening through a side of the interior sleeve, the inlet being closed by walls of the support when the interior sleeve is moved downwardly, a cleaner member carried by the upper end of said interior sleeve, means closing the upper end of said interior sleeve while providing said outlet for cleaning fluid through said cleaner member, an independent cleaner member carried by said exterior sleeve in coacting relation to the aforesaid cleaner member, and means for rotating the sleeves and cleaner members carried thereby when the inner sleeve is moved vertically for cleaning the interior and exterior surfaces of a glass or other article inserted between the cleaner members.
